UNITED STATES PATENT OFFICE.

SALLY M. LODEWICK, OF NEW YORK, N. Y.

DESIGN FOR A LADY'S POCKETBOOK.

Application filed May 22, 1928. Serial No. 26,807. Term of patent 3½ years.

To all whom it may concern:

Be it known that I, SALLY M. LODEWICK, a citizen of the United States, residing at 471 Park Avenue, New York city, in the county of New York and State of New York, having invented a new, original, and ornamental Design for Lady's Pocketbook, of which the following is a specification, reference being had to the accompanying drawings, forming part thereof.

The figure is a perspective view of the pocket-book constituting the design wherein the ornamentation consists of the figure of a dog with a leash attached to the upper right hand corner of the pocket book.

I claim:

The ornamental design for a lady's pocket book, as shown and described.

SALLY M. LODEWICK.
